United States Patent Office

Des. 188,277
Patented June 28, 1960

188,277

GIRDLE

William J. Dorsey, 223 W. Wyoming Ave., Dover, Del.

Filed Dec. 7, 1959, Ser. No. 58,581

Term of patent 14 years

(Cl. D20—2)

FIG.1.

FIG.2.

I claim:

The ornamental design for a girdle, substantially as shown.
